(57) **CLAIM**

The ornamental design for a portable electric driver body, as shown and described.

DESCRIPTION

FIG. 1 is a front, left and top perspective view of a portable electric driver body showing my new design;

FIG. 2 is a rear, right and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the drawings illustrate portions of the portable electric driver body which form no part of the claimed design. The dot-dash broken lines represent the boundary of the claimed design and form no part of the claimed design. The faded portions outside the dot-dash broken lines illustrate portions of the article that form no part of the claimed design.
